DESIGN FOR A BRUSH

Frank R. Weber, Troy, N. Y., assignor to Mohawk
Brush Company, Albany, N. Y., a corporation of New York

Application March 21, 1939, Serial No. 83,735

Term of patent 14 years

To all whom it may concern:

Be it known that I, Frank R. Weber, a citizen of the United States residing at Troy, in the county of Rensselaer and State of New York, have invented a new, original, and ornamental Design for a Brush, of which the following is a specification, reference being had to the accompanying drawing forming a part thereof.

Figure 1 is a top plan view of a brush showing
my new design;

Figure 2 is a side elevational view; and

Figure 3 is an end elevational view thereof.

I claim:

The ornamental design for a brush, as shown.

FRANK R. WEBER.
